UNITED STATES PATENT OFFICE.

FREDERICK SMITH, OF DARBY, PENNSYLVANIA.

SUPPORTING AND LOCKING DEVICE.

1,242,731.

Specification of Letters Patent. Patented Oct. 9, 1917.

Application filed May 16, 1916. Serial No. 97,970.

To all whom it may concern:

Be it known that I, FREDERICK SMITH, a citizen of the United States, residing at Darby, in the county of Delaware and State 5 of Pennsylvania, have invented new and useful Improvements in Supporting and Locking Devices, of which the following is a specification.

An object of the invention is to provide 10 a device for supporting and locking an element in position to prevent use of the latter until a toll for the use of the element has been registered or paid.

The invention is particularly adapted to 15 the receivers of telephones in instances where the proprietor of a store, or the like is put to the trouble and expense of notifying a neighbor that he or she is desired at the telephone of the proprietor to answer 20 a phone call by another party, who being unable to communicate direct with the neighbor, telephones to the store nearest the neighbor's home or in the immediate vicinity. In a situation of this character, where 25 there is no lock or other device provided for retaining the telephone or a part thereof in an inoperative position until the store keeper is compensated for the time of his clerk in calling the party to the phone, it 30 has been found that the act of the proprietor or storekeeper is regarded in the nature of a favor and even despite notices conspicuously posted, regarding a toll for this character of service, the proprietor receives no 35 compensation for the services of his clerk, store and phone placed to the use and interest of the person called to the instrument to answer the call.

With this in mind I provide a device that 40 can be conveniently attached to a wall, bracket or to a table or other surface and with which the receiver of the telephone is associated and locked after the proprietor has answered the summons to the phone and 45 has been asked to send his clerk to a neighboring house to summon the desired person to the phone. Now when the party wanted reaches the phone it will be necessary for the former to deposit a coin in the device 50 in order to work the unlocking of the receiver so that the phone can be used. Thus the proprietor of the store is assured of the toll specified by him as being sufficient to pay for the trouble and expense he has been 55 put to in order to bring the desired party to his telephone.

In the further disclosure of the invention, reference is to be had to the accompanying drawings, constituting a part of this specification in which similar characters of reference denote corresponding parts in all the views, and in which—

Fig. 1 is a perspective view of the device showing the same in use,

Fig. 2 is a vertical longitudinal sectional view taken through the device,

Fig. 3 is a horizontal sectional view taken on the line 3—3 of Fig. 2,

Fig. 4 is a transverse sectional view taken on the line 4—4 in Fig. 2, and

Fig. 5 is a perspective view of mechanism removed from its casing.

Fig. 6 is a side elevation of a slightly modified form of the invention, showing the same in use;

Fig. 7 is a vertical section;

Fig. 8 is a perspective view of the locking device removed from the casing; and

Fig. 9 is a plan view of the locking device assembled.

Referring more particularly to the views, I disclose a casing 10 of a substantially cylindrical formation, the inner end of the casing being formed to fit over the circular flange 11 of a back 12, suitably secured to 85 a wall 13. A locking bar 14 is mounted to turn in bearings 15 in the casing and has a reduced portion 16 received in a bayonet slot 17 of a projection 18 on the back 12, when the locking bar is turned so that the 90 reduced portion can readily pass into the narrow portion of the slot. A subsequent quarter turn of the locking bar, when the reduced portion lies in the large portion of the bayonet slot, tends to lock the locking 95 bar relative to the projection 18 as shown in Fig. 2 thus locking the casing 10 to the back 12 as will be readily perceived. The turning of the locking bar 14 can be readily accomplished from the exterior of the casing 100 by inserting a key (not shown) in an opening 19 communicating with one of the bearings 15, and which for this purpose is tubular throughout, thus enabling the key to be engaged with an end of the locking bar to 105 turn the same as desired.

The casing 10 is provided near its front end with a wall 20 having an opening 21, the wall being spaced from the front edge of the casing and in fact forming two chambers, 22, 23, the former being for the reception of the mechanism and also constituting

a coin box while the latter chamber 23, receives the head end 24 of a telephone receiver 25. It will be noted that a shield or guard 26 is provided immediately adjacent 5 the front end of the casing, said shield forming a wall portion for one end of the chamber 23 and constituting a holding means for the telephone receiver as will hereinafter more clearly appear.

10 The wall 20 supports, on its inner face, a segmental element or frame 28 having lugs 29 projecting rearward from the frame to swingingly support a locking element 30, in the nature of an arm, and formed at 15 its front end into a gripping member 31 and a somewhat curved or hooked handle 32, the front end of the casing 10 at its top being provided with a longitudinal slot 33 in which the locking element operates and 20 a cross slot 34 for the reception of a coin. An escutcheon 35 is soldered or otherwise secured to the casing and has slots 36, 37 registering with the slots 33, 34, thus facilitating the guiding of the locking element 25 30, in its movement. The rear end of the locking element 30 is formed to provide a depending coin chute 38, normally in registration with the slot 34. The coin chute 38 is arranged in superposition to a latch 39 30 pivoted on the frame 28, the latch having a depending balancing tail 40 at its rear end and terminating at its front end in an extension or handle 41 projecting into the opening 21 in the wall 20, a tongue 42 35 formed with the latch being arranged to extend rearwardly beyond the pivotal mounting of the latch and into an opening 43 in the coin chute 38.

In the use of the device described I will 40 assume that a person has phoned to a store having a telephone and the structure described and that it is desired that the proprietor of the store send out for the party wanted at the phone, the proprietor in such 45 an instance being entitled to charge a toll for the service rendered. The proprietor therefore places the head end of the receiver 25 in the chamber 23 as shown in Figs. 1 and 2 and then pulls downwardly on the 50 locking element 30, causing the member 31 to project over the edge of the head and with the ledge or shield 26, hold the receiver from falling. As the element 30 is pulled down the tail 40 tending to swing the latch 55 39 will cause the tongue 42 to project into the opening 43 and as the tongue will thus tend to engage the wall of that opening or in other words, a part of the coin chute 38, when an attempt is made to pull the locking 60 element upwardly, the point of engagement of the tongue with the coin chute being beyond the pivotal mounting of the latch will result in the element 30 being locked against an upward movement, thus holding the receiver 65 against removal from the chamber

23. It will be clearly seen that if an obstruction were placed in the path of movement of the tongue 42, projecting through the opening 43, that this would result in a swinging of the latch to move the tongue 70 out of the vertical plane of the coin chute, when an upward movement is imparted to the locking element 30. Therefore until an obstruction is provided the receiver will be locked and in the position shown in Fig. 1. 75

The obstruction to be provided, however, is the coin 44, and when the same is dropped into the slot 37, by the party called to the telephone, the coin, dropping into the coin chute and held therein by having an edge 80 resting against the latch and by guideways 45 on the chute, will constitute the desired obstruction, and being now engaged by the tongue 42; when the element 30 is pulled upwardly, the resultant swinging of the latch 85 will permit of swinging the element 30 out of engagement with the telephone receiver so that the latter can be removed from its formerly locked position and used in the usual manner, the coin in the meantime 90 dropping into the chamber 22, forming a coin receptacle as mentioned heretofore.

Thus the proprietor of the store is paid for the services rendered in calling the person to the phone and for each call and service so rendered receives his just compensation, deposited in my device in order that the receiver can be removed therefrom and placed to the ear of the summoned party. Should the coin mechanism for any reason 100 fail to work on account of an over abundance of coins in the coin box, the proprietor can, with his key, unlock and remove the casing from the back so that the former can be placed to the ear and constitute a supplementary receiver, this, however, being only necessary and practical when it is desired to bring the receiver quickly into use after it has been locked and the mechanism, for the mentioned or other reasons, fails to operate. 105

Should malicious persons or children tamper with the element 30, when the device is not in use, and perchance pull downwardly upon the former thus locking it so that the 115 receiver cannot subsequently be placed with its head in the chamber 23, it will be clear that it is only necessary to insert the finger through the opening 21 to press down on the handle 41 and move the latch so that 120 the element 30 will be unlocked and can be raised to permit of inserting the head of the receiver into the chamber 23.

In the modified form of the invention, which has been illustrated in Figs. 6 and 9 125 of the drawings the same consists of a casing 50, which is adapted to be placed upon a suitable support 51, preferably at a point adjacent a telephone 52. The casing 50 consists of a metallic box like structure having 130

a removable pivoted top 53, secured thereto, said top being normally locked in the casing 50 by the lock mechanism 54, but may be readily removed from said casing so that 5 the interior of the latter will be readily accessible. A plate 55 is secured to the top 53 and is employed as a seat for the reception of the telephone receiver 56, when the latter is positioned upon the casing for the 10 above specified purposes.

Secured to the under face of the top 53, and normally lying within the interior of the casing 50, is a frame 57, to which is pivotally connected a receiver locking element 58, the latter comprising a collar shaped gripping member 59 which is employed to surround the lower end of the receiver, as shown in Fig. 7, when in an active position. The element 58 also embodies a depending arm 59', which extends into the casing 50 through a slot 60, formed in the top 53 and is rigidly or integrally formed with the collar shaped gripping member 59. A stud 61, projecting outwardly from the frame 57, forms a support and a fulcrum for the locking element 58, and the latter is provided with an offset locking lug 62 which coöperates with the upper extremity of a locking latch 62', pivoted as at 63 to the frame 57, when the receiver 56 is locked in engagement with the casing.

A coin chute 64 is rigidly secured to the locking element 58 and the upper coin receiving extremity 65 thereof is positioned in alignment with a coin receiving slot 66 formed in the top 53, when the element 58 is in a locked position. The lower extremity of the chute 64 terminates contiguously to 35 a slot 67 formed in the lower end of the arm 59'. The latch 62' is provided with a tongue 68, which, when the latch is in a locking position, extends across the upper portion of the slot 67, so as to be engaged by a suitable coin to effect the release of the receiver, in a manner to be presently set forth. A coiled spring 69 is wound about the stud 61 and normally exerts a pressure upon the element 58 so that the latter will 45 be maintained in an elevated or inactive position, when said element is permitted to operate independently of the latch 62'.

Briefly stated, the operation of the modified form is substantially as follows: The 50 receiver 56 is locked within the collar-shaped gripping member 59 by inserting the lower end of said receiver within the chamber of said collar. The element 58 is then lowered until the receiver rests upon 55 the plate 55, which permits the latch 62' to gravitate into locking engagement with the lug 62 of the arm 59', thus preventing the collar from moving upwardly and thereby retaining the receiver in a locked condition.

In order to release the receiver, so that it may be used, a coin is inserted into the chute 64, and is caused to gravitate downwardly into engagement with the tongue 68 of the latch 62', so that the latter will be 60 rocked upon the fulcrum 63, thereby releasing the element 58 to permit the collar to be elevated whereby the release of the receiver is effected. If the collar should accidentally become locked when the receiver is not in 65 engagement therewith, said collar may be readily unlocked by operating a lever 71, rigidly secured to the latch 62'. This action is accomplished by providing an opening 72 in the plate 55, whereby the lever 71 may be 70 readily actuated without removing the top or cover 53. After the coins have fulfilled their function in unlocking the receiver, the same will drop into the bottom of the casing 50, and may be readily collected by operating the locking mechanism 54 so that the top or cover 53 may be removed from 75 the casing.

Having described my invention, I claim:

1. A device for telephone receivers comprising a casing for the reception of the receiver, a frame in the casing, a locking element pivoted on the frame, and having engagement with the receiver to secure the same in the casing, a latch for holding the locking element against movement, a support, and means for locking the casing to 90 said support.

2. A supporting and locking device for telephone receivers embodying a back, a 100 casing removably connected with the back, and having a chamber therein for the reception of the receiver, means for locking the casing to the back, a locking element for holding the receiver in said chamber, and 105 means coöperating with the locking element to secure the locking element against movement.

3. A supporting and locking device for telephone receivers embodying a casing 110 adapted to have the receiver connected therewith, means for locking the receiver to the casing, a back, and means for locking the casing to said back.

4. A supporting and locking device for a 115 body comprising a casing, an apertured partition therein, a locking element, a pivoted member arranged adjacent the aperture in the partition to be manually operated when the body is not connected with the casing 120 and adapted to coöperate with said locking element for locking the body to said casing.

5. A supporting and locking device for a 125 body comprising a casing for supporting the body and formed to provide a passage for gaining access to the interior of the casing when the body is disconnected from said casing, a locking element in said casing, a latch adapted to coöperate with the locking ele- 130

ment and accessible by way of said passage, said body when connected with the casing obstructing the passage to prevent access to said latch.

5 6. A supporting and locking device for telephone receivers comprising a casing for the reception of the receiver and adapted to form a continuation thereof to provide an ear piece and means for locking the receiver and casing against relative disengagement.

10 7. A device for telephone receivers embodying a casing for the reception of the receiver, a pivoted locking element operable for securing the receiver to said casing, a latch co-acting with the locking element for retaining the latter in locked position, means formed on said latch with which a coin engages for causing an automatic release of the same from the locking element, and means carried by said latch for permitting of a manual release of the latch from said locking element substantially as and for the purpose specified.

15 8. A device for telephone receivers embodying a casing for the reception of the

receiver, a locking element for securing the receiver locked to said casing; a coin chute on said element, a latch for holding the locking element in locked position, and a tongue formed integral with said latch and 30 arranged to project into the coin chute substantially as and for the purpose specified.

9. A device for telephone receivers comprising a casing for the reception of a receiver and having an opening, a pivoted operating element operable for securing the receiver to said casing, means preventing the operation of the locking element previous to the deposit of a coin, and means disposed in juxtaposition with the opening of said 40 casing for permitting of a manual release of the former mentioned means from the locking element.

In testimony whereof I affix my signature in presence of two witnesses.

FREDERICK SMITH.
